Primary Examiner — Marcus Jackson(74) *Attorney, Agent, or Firm* — Banner & Witcoff, Ltd.**(57) CLAIM**

The ornamental design for a light bulb, as shown and described.

DESCRIPTION

The FIGURE is a front perspective view of a light bulb showing my new design.

The broken line showing of the remainder of the light bulb and the base is for environmental purposes only and form no part of the claimed design.

1 Claim, 1 Drawing Sheet(56)
